UNITED STATES PATENT OFFICE.

WINFIELD S. HUSON, OF DERBY, CONNECTICUT, ASSIGNOR TO THE WHITLOCK PRINTING PRESS MFG. CO., OF DERBY, CONNECTICUT, A CORPORATION.

FLAT-BED CYLINDER PRINTING-PRESS.

SPECIFICATION forming part of Letters Patent No. 752,291, dated February 16, 1904.

Application filed July 20, 1903. Serial No. 186,240. (No model.)

To all whom it may concern:

Be it known that I, WINFIELD S. HUSON, of Derby, in the county of New Haven and State of Connecticut, have invented a new and useful Improvement in Flat-Bed Cylinder Printing-Presses; and I do hereby declare the following, when taken in connection with the accompanying drawings and the letters of reference marked thereon, to be a full, clear, and exact description of the same, and which said drawings constitute part of this specification, and represent, in—

Figure 1, a broken view, in side elevation, of a printing-press provided with my improved impression and tripping mechanism, the cylinder being shown in its elevated or non-printing position and the tripping mechanism in its normal position; Fig. 2, a broken view, in side elevation, of one pair of the cylinder-box jaws with the outer bushing of the eccentric removed to show the eccentric in its printing position; Fig. 2^a, a corresponding view with the eccentric set to take a different printing position; Fig. 3, a broken view, in rear elevation, of portions of the impression mechanism with the bushings and the step of the eccentric in vertical section; Fig. 4, a plan view of one pair of the cylinder-box jaws; Fig. 5, a broken plan view of the tripping mechanism; Fig. 6, a broken view, in side elevation, of the tripping mechanism with the parts thereof in the safety positions taken by them when the cylinder is in its printing position; Fig. 7, a corresponding view showing the engagement of the guard-roll with the guard-surface on the gab-hook just after the same has begun to draw down the cylinder.

My invention relates to an improvement in that class of flat-bed cylinder printing-presses in which the cylinder is lifted clear of the form to permit the reciprocating type-bed to make its return movement.

More particularly, my invention relates to an improvement in the "impression" mechanism and in the "tripping" mechanism of such presses, the former being the mechanism employed for raising the cylinder into its elevated or clearance position and lowering it

into its depressed or printing position and for holding it in each position and the latter being the mechanism employed for temporarily suspending the raising and lowering operation of the cylinder by disconnecting the same from the power at the time when it is in its elevated or clearance position.

The main objects of my invention are to provide such presses with simple, durable, and powerful impression mechanism constructed with particular reference to permitting the cylinder to be readily removed and replaced and the parts of the said mechanism to be accessible for attention, repair, and adjustment, and, further, to produce a tripping mechanism of simple and reliable action and constructed with particular reference to safeguarding the manual or non-automatic release of the cylinder from its elevated or clearance position at any other but the right moment, even though the pressman accidentally or when excited depresses the foot-tread of the tripping mechanism.

With these ends in view my invention consists in certain details of construction and combinations of parts, as will be hereinafter described, and pointed out in the claims.

It may be well to say at the outset that inasmuch as the impression mechanism is duplicated at each end of the impression-cylinder a description of one mechanism will suffice for both. That on the right-hand side of the press will be chosen for the purpose.

The impression-cylinder 2 has its right-end journal 3 supported in a two-part journal-box, comprising an upper part 4 and a lower part 5, secured together by bolts 6 passing through the upper part 4 and threaded into the lower part 5. The said parts of the journal-box are formed upon their outer corners with guide-ribs 7, coacting with guide-ribs 8, formed at the corners of the upright cylinder-box jaws 9, produced by centrally cutting away the upper end of the upright 10 of the right-hand side frame 11 of the press to form the rectangular journal-box opening 12.

The lower part 5 of the two-part journal-box is formed with an integral depending

plate-like part, which, for convenience, I shall hereinafter speak of as the "bearing-plate" 13. This plate extends downwardly into a vertical recess or chamber 14, formed in the upright 10 aforesaid, leading out of the bottom of the box-opening 12 and having an outer wall 10^a and an inner wall 10^b. A rectangular opening 15, Fig. 2 and Fig. 2^a, formed in the said bearing-plate 13, receives the eccentric-step 16, upon which the eccentric 17 rests, the upper edge of the eccentric bearing, as shown, directly against the upper wall of the opening 15, against which it acts to assist, if need be, in lifting the cylinder. The two journals 18 18 of the eccentric 16 are mounted in flanged eccentric bushings 19 19, set into bushing-openings 20, located opposite each other in the outer and inner walls 10^a and 10^b of the upright 10 and opening into the said chamber 14. I may here state that by making the bushings 19 eccentric in form the bushing-openings 20 may be made small enough not to weaken the upright 10 and yet large enough to permit the ready introduction into and removal from the chamber 14 of the eccentric 16 and its step 17 in assembling and in dismounting the press or in any examination thereof.

It will of course be understood that by turning the eccentric 17 in one direction or the other the same will act through the bearing-plate 13 and the two-part journal-box, above described, to raise or lower the impression-cylinder through the very short distance required for bringing it into contact with the type on the type-bed and for clearing it from contact with such type.

In order to relieve the eccentric in whole or in part from the task of lifting the cylinder from its printing to its clearance or non-printing position, I employ a heavy spiral counterbalance-spring 21, located in a spring-chamber 22, formed in the upright 10 and leading out of the bottom of the said chamber 14. This spring bears at its upper end against a washer 23, carrying a heavy screw 24, which impinges directly against the square lower edge of the bearing-plate 13, to which it transmits the lifting effect of the spring, which will be so proportioned in power to the weight of the cylinder that it will virtually counterbalance the same with just enough power on the side of the spring to cause the same to lift the cylinder without the aid of the eccentric, although the engagement of the eccentric with the upper wall of the opening 15, as described, enables the eccentric to act to assist the spring or to take its place should it give out or be removed. The cylinder descends from its non-printing into its printing positions against the power of the spring by its own gravity, together with the downward thrust of the eccentric, which, it will be understood, positively holds the cylinder in its elevated position as well as in its printing posi-

tion, and therefore when the printing is actually being done.

For the oscillation of the eccentric 16 I employ an arm 25, clamped upon its outer journal 18 and extending rearwardly therefrom. The outer end of this arm is pivotally connected with the upper end of a two-part connecting-rod 26, the parts of which are united by having their ends oppositely threaded and entered into an adjusting-sleeve or union-nut 27, having right and left hand threads. By turning the said sleeve or union-nut the rod is virtually made shorter or longer, as may be required, to increase or decrease the pressure of the cylinder on the form or type. Jam-nuts 27^a, located at the ends of the sleeve or nut 27, prevent the same from turning after the rod has been adjusted. The lower end of the said two-part connecting-rod is pivoted to a rock-arm 28, secured to a rock-shaft 29, arranged transversely with respect to the frame of the press and provided at its opposite end with the corresponding rock-arm of the duplicate impression mechanism at the other end of the cylinder.

For the oscillation of the rock-shaft I provide it with a bifurcated gab-hook arm 30, furnished with a gab-hook or coupling stud 31 for engagement by a reciprocating gab-hook 32, entering between the two members 95 of the arm 30 and located upon the rear end of a gab-hook bar 33, the forward end of which is pivotally connected with the upper end of a cam-lever 34, swinging on a pivot 35 in the base of the press and carrying a cam-roller 36, traveling in a cam-path 37 in the impression-cam 38, which is mounted upon the cam-shaft 39 of the press and which makes one complete revolution for two revolutions of the impression-cylinder and for one complete movement back and forth of the reciprocating type-bed. The cylinder 2 and the cam-shaft 39 may be driven in any approved manner—as, for instance, by the devices shown in United States Patent No. 725,714. Under this construction the gab-hook bar 33 and gab-hook 32 are reciprocated back and forth; but it will be seen by examining the form of the cam-path 37 that the hook and bar will pause at the opposite limits of their stroke, these limits respectively representing the elevated or non-printing and the depressed or printing positions of the cylinder.

A safety-roll mounted upon a pin 41 in the outer end of the gab-hook arm 30 coacts with a guard 42, formed upon the gab-hook and consisting of a cam-like surface arranged in position to be engaged by the said roll under certain conditions, as will be explained later on, the said roll and guard forming features of my improved tripping mechanism, which is employed to temporarily suspend the lowering of the impression-cylinder in case the pressman should fail to feed a sheet or a sheet should go wrong, or for some other reason

making it desirable to retain the cylinder in its elevated or clearance position.

As herein shown, my improved tripping mechanism comprises a foot-tread 43, Fig. 5, mounted upon the upper end of a stem 44, extending upward through the platform 45, on which the pressman stands, and downward through an opening 46, having its upper and lower ends flared and formed in an arm 47, secured to a shaft 48, journaled in a bracket 49, depending from the frame 11. A collar 50, mounted upon the stem 44, engages with the upper face of the arm 47, so that the same will be depressed and the shaft 48 turned when the pressman puts his foot upon the foot-tread 43 and pushes the stem 44 downward. To the opposite or inner end of the rock-shaft 48 I secure an arm 51, carrying a swiveled head 52 traversed by a central opening 52^a, receiving the rod-like shank 53 of a coupling or lifting link 54, the elongated opening 55 of which receives a tripping-pin 56, mounted in the end of the gab-hook extension 57. This slot-like opening 55 is made considerably longer than the thrust of the foot-tread stem 44 to assist in carrying out the safety function of the tripping mechanism, as will appear later on. A coiled spring 58, encircling the lower portion of the shank 53, has its upper end secured to the swiveled head 52 and its lower end secured to the upper portion of the link 54. This spring is normally not under tension and becomes operative only when the foot-tread 43 is depressed, whereby the elevation of the arm 51 moves the swiveled head 52 outward on the shank 53, and thus stretches the spring, which then begins to exert an effort to lift the link 54, but without effect on the gab-hook unless the pin 56, carried by the gab-hook extension, is engaged at this time with the lower end wall of the slot 55 in the link.

In the normal or what I may call "uninterrupted" operation of the press the gab-hook 32 remains in unbroken engagement with the gab-hook stud 59 in the gab-hook rock-arm 30, which when so coupled with the gab-hook is continuously swung back and forth for the positive oscillation of the eccentric, whereby the cylinder is operated. During this time the tripping mechanism is automatically operated, though idly or without effect, by reason of its connection through the pin 56 with the gab-hook extension 57, which moves it through all of the positions intermediate between the position which it takes when the cylinder is elevated, as shown in Fig. 1, and the position which it takes when the cylinder is down, as shown in Fig. 6.

The tripping mechanism is brought into play to interrupt or temporarily suspend the above-described normal or regular action of the press by cutting out, so to speak, the impression mechanism, so as to prevent the power of the cam-shaft 39 from being trans-

mitted to the cylinder for the operation thereof. Specifically, the tripping mechanism cuts off the power from the cylinder by uncoupling the gab-hook from the gab-hook stud. In order to prevent accidents, the cylinder must be cut out when it is held in its lifted position. To cut it out at any other time might result in breakage. Now the parts are constructed and arranged and timed in their action so that when the cylinder is held in its elevated or clearance position the parts of the tripping mechanism will have the positions in which they are shown in Fig. 1, with the tripping-pin 56 located at the bottom of the opening 55 in the lifting-link 54. If with the parts in these positions the tread 43 is depressed, the spring 58 will be placed under sufficient tension to enable it to lift the link and with it the gab-hook, which will be raised sufficiently to disengage it from the gab-hook or coupling stud 31, whereby the power of the cam-shaft is cut off from the eccentric. The gab-hook, it should be here remarked, is free to be raised, as described, at this time, because the safety-roll 40 is in a clearance position with respect to the cam-like guard 42, located upon the hook itself. Just as soon as the gab-hook is disengaged from the gab-hook stud the gab-hook, although continuing to reciprocate back and forth, will not, as stated, communicate any of the motion of the cam-shaft 39 to the eccentric. The cylinder will therefore remain at rest in its elevated position until pressure has been removed from the tread 43, which takes the tension off from the spring 54 and allows the gab-hook to descend by gravity and reengage with the stud 31.

With reference now to the safe-guarding functions of the roll 40 and cam-like guard 42 it has been found in practice that a pressman through inadvertence or excitement is very liable to step or jump on the foot-tread 43, and thus place the spring of the tripping mechanism under tension and ready for operation at a time when the tripping function of the tripping mechanism cannot safely be brought into play. Here the roll and guard step in, so to speak, and prevent any accident which might result from the untimely lifting of the gab-hook, for substantially from the time the cylinder leaves its elevated and locked position to the time it returns to that position the roll 40 is engaged with the cam-like guard over which the roll rides back and forth, with the effect of keeping the gab-hook locked down, as it were, in engagement with the gab-hook stud. The roll, however, rides off the guard and is lifted above the same, as shown in Fig. 1, when the cylinder is lifted into its elevated position and remains so cleared from the guard long enough to cover the period in which it is designed to have the tripping mechanism operative. No matter, therefore, when the pressman depresses the foot-tread and no matter whether he holds it down or

not or how long, no matter how untimely he is about it or how excited the tripping mechanism cannot operate to cut off the power from the eccentric until the cylinder is in its 5 elevated and therefore safe position.

The untimely depression of the foot-tread is also nullified by the angle at which the lifting link is placed with respect to the gab-hook, whereby the tripping-pin moves away from

- 10 the lower end of the opening in the lifting-link so rapidly that the action of the link upon the pin would be nullified even if the spring should be put under tension at any time except the right time, for the reason that the link will
- 15 not, of course, act to lift the hook except when the pin is at the bottom of the opening in the link. For instance, should the tread be depressed when the cylinder is down the spring would be placed under tension and the link
- 20 lifted, but without any effect upon the gab-hook, as the tripping-pin at such time would be at the upper end of the opening of the link, as shown in Fig. 6. But suppose the press-man should jump upon the foot-tread 43 just
- 25 as the gab-hook 32 is starting rearward to effect the lowering of the cylinder 2, and thus place the spring 58 under tension before the tripping-pin 56 has moved away from the lower end of the slot 55 in the link 54 for a
- 30 distance equal to the downward movement of the stem 44, on which the foot-tread is mounted. Under these circumstances the tripping mechanism might operate during the lowering of the cylinder; but for the fact that the guard-
- 35 roll 40 moves in an arc of a larger circle than the gab-hook stud 31, whereby the roll moves rearward faster than the tripping-pin 56 with the effect of bringing the roll into engagement with the cam-like guard-surface 42, as shown
- 40 in Fig. 7. In this way the period immediately following the beginning of the downward movement of the cylinder is covered by the safety functions of the guard-roll and cam-like guard-surface.
- 45 By preference I construct and arrange the parts so that when the cylinder is in its depressed or printing position the center line of the connecting-rod 26 will intersect the axis of the rock-shaft 29, as shown in Fig. 6, thus
- 50 forming a lock and preventing the arm 25 from being raised by any other means than the oscillation of the shaft 29, so that when the impression-cylinder is in its printing position it is securely held there by the alignment of
- 55 these centers.

- As it may not always be convenient to adjust the vertical movement of the cylinder to the right impression contact with the type by means of the union nut or sleeve 27 on the connecting-rod 26, I provide for adjusting the eccentric bushings 19, which accomplishes the same result. To this end I furnish each bushing with an arm 60, Fig. 4, and connect the ends of the arms by a tie-rod 61, the upper
- 60 and lower faces of which are respectively en-

gaged by set-screws 62, mounted in brackets 63, projecting from the forward edge of the forward journal-box 9. By properly adjusting these screws the eccentric bushings may be shifted, with the effect of raising or lowering 70 the eccentric 17, and hence of "placing" the movement of the cylinder as desired with respect to the type-bed. While it is not essential to provide for both of these two different modes of adjusting the vertical movement of the cylinder, as one might be employed to the exclusion of the other, I illustrate both, as under some circumstances one adjustment might be better than the other, and vice versa. Furthermore, in some presses the adjustment of the 75 connecting-rod 26 may not be at all convenient or possible, owing to its inaccessibility. In case provision is made for the adjustment of the eccentric bushings the parts may be set, so that when the cylinder is in its down position, 80 as shown in Fig. 2^a, the center of the eccentric will be in line with the vertical axis of the journal of the cylinder, which will thus be locked in its down position on the principle already described of so locking it by 85 bringing the longitudinal center of the connecting-rod 26 into line with the vertical center of the rock-shaft 29.

My improved impression mechanism is not only simple and compact in character, but far 90 more direct in its action upon the impression-cylinder than the devices of the prior art, and therefore requires less power for its operation and is more reliable in its action. All this is due in large part to the location of the eccentrics in bearing-plates depending from the journal-boxes of the cylinder and mounting the journals of the eccentrics directly in the frame of the machine at points comparatively close to the journals of the cylinder. I thus 95 avoid the use of the long rods heretofore employed to transmit to the cylinders the action of the eccentrics, which in the prior devices have been located at some distance from the cylinder. These rods stretch during the impression period and do not hold the cylinder down to the work as rigidly as with my device, in which the eccentrics are located very close to the journals of the cylinder and in which the use of the long rods is avoided. 100 At the same time the eccentrics and the parts immediately connected with them are readily accessible for attention and repair and are easily removed for the removal of the impression-cylinder itself. Under my construction 105 the main burden of carrying the cylinder is still left with the frame of the machine instead of being transferred to the impression devices. The counterbalance-springs being mounted in the frame itself and acting directly 110 upon the bearing-plates of the journal-boxes of the cylinder are very effective in operation and relieve any side strain.

My improved tripping mechanism is simple 115 in its character, and by the construction 120

pointed out is rendered inoperative except when it may be safely operated even though the pressman in his excitement may depress the foot-tread and hold it depressed for some time.

In view of the modifications suggested and of others which may obviously be made I would have it understood that I do not limit myself to such construction, but hold myself at liberty to make such departures therefrom as fairly fall within the spirit and scope of my invention.

Having fully described my invention, what I claim as new, and desire to secure by Letters Patent, is—

1. In a flat-bed cylinder printing-press, the combination with the frame thereof, of a two-part journal-box mounted therein, a cylinder having a journal which bears in the said two-part box, and an eccentric mounted in the said frame close to the said journal and acting thereupon through the lower member of the said box to move the cylinder to the printing-line of the press.

2. In a flat-bed cylinder printing-press, the combination with the frame thereof, of a two-part journal-box mounted therein, a cylinder having a journal which bears in the said two-part box, an eccentric mounted in the said frame close to the said journal and acting thereupon through the lower member of the said box for moving the cylinder to the printing-line of the press, and a counterbalance-spring mounted in the frame and acting through the lower member of the said box to move the cylinder away from the said printing-line.

3. In a flat-bed cylinder printing-press, the combination with the frame thereof, of a two-part journal-box mounted in the said frame and having its lower member formed with an integral depending bearing-plate, a cylinder having a journal which bears in the said two-part box, an eccentric mounted in the said frame close to the said plate and coacting therewith to move the cylinder to the printing-line, and a counterbalance-spring mounted in the said frame and coacting with the said plate to lift the cylinder from the printing-line.

4. In a flat-bed cylinder printing-press, the combination with the frame thereof, of a two-part journal-box mounted therein, an impression-cylinder having a journal which bears in the said two-part box, an eccentric mounted in the said frame close to the said journal and coacting with the lower member of the said two-part box to move the cylinder to the printing-line of the press, means for adjusting the said eccentric to shift the position of the cylinder with respect to the said printing-line, and a counterbalance-spring mounted in the said frame and coacting with the lower member of the said two-part box to lift the cylinder from the said printing-line.

5. In a flat-bed cylinder printing-press, the combination with the frame thereof, of a two-

part journal-box mounted therein, a cylinder having a journal which bears in the said two-part box, an eccentric mounted in the said frame close to the said journal and coacting with the lower member of the said two-part box to move the cylinder to the printing-line of the press, eccentric bushings for the said eccentric, means for adjusting the said bushings for changing the position of the eccentric and hence the cylinder with respect to the said printing-line, and means for oscillating the eccentric for the operation of the cylinder.

6. In a flat-bed cylinder printing-press, the combination with the cylinder thereof, of an eccentric, eccentric bushings for the journals of the said eccentric, arms attached to the said bushings, and set-screws coacting with the said arms to shift them for changing the positions of the bushings with respect to the journals of the eccentric.

7. In a flat-bed cylinder printing-press, the combination with a frame having cylinder-box jaws, of a two-part journal-box mounted in the said jaws, a cylinder having a journal which bears in the said two-part box, an integral bearing-plate depending from the lower member of the said two-part box, an eccentric journaled in the frame below but close to the said jaws and acting directly upon the said plate to move the cylinder to the printing-line of the press, power connections for operating the said eccentric, and a counterbalance-spring mounted in the frame and coacting with the said plate to lift the cylinder from the said printing-line.

8. In a flat-bed printing-press, the combination with a frame having a pair of journal-box jaws and a chamber, of an impression-cylinder, a journal-box therefor provided with a bearing-plate entering the said chamber, an eccentric coacting with the said plate, bushings located in the walls of the said chamber and receiving the journals of the eccentric, and power connections for oscillating the said eccentric.

9. In a flat-bed cylinder printing-press, the combination with a frame having a pair of cylinder-box jaws, of a two-part journal-box mounted therein, a cylinder having a journal which bears in the said two-part box, an integral bearing-plate depending from the lower member of the said two-part box, an eccentric mounted in the frame, located below the said jaws and entering the said bearing-plate through which it acts to move the cylinder to the printing-line of the press, and a counterbalance-spring mounted in the frame, located below and close to the said plate and acting thereupon to lift the cylinder from the said printing-line.

10. In a flat-bed cylinder printing-press, the combination with the impression-cylinder thereof, of impression mechanism for raising and lowering the cylinder, tripping mechanism coacting with the said impression mechan-
